Attorneys.

UNITED STATES PATENT OFFICE.

HUGO JUNKERS, OF DESSAU, GERMANY.

STARTING INTERNAL-COMBUSTION ENGINES.

Application filed November 5, 1921, Serial No. 513,086, and in Germany May 2, 1921.

My invention relates to internal combustion engines and more especially to the means for starting such engines by compressed air. It is an object of my invention to simplify 5 the starting operation in engines to which fuel is supplied by a pump in synchronism with the working of the engine. As a rule such engines are started by aid of starting valves provided in some or all of the working cylinders and separate valve gear adapted to be thrown in and out for operating said valves. Such valve gears involve the drawback that their accommodation is connected with difficulties and that they render 10 the engine complicated. It has therefore, been proposed to accommodate the starting valves of several cylinders in separate casings whereby their operation is rendered somewhat simpler. However this arrangement still requires special valve gears and means for throwing the starting valves in and out.

According to my invention, I operate the starting valves by means of the fuel pump gear. I thus obtain the advantage that 25 special gears for the starting valves are entirely dispensed with and the engine is very much simplified. Further, the operation of the engine is greatly facilitated and 30 errors rendered impossible so that the engine does not require a thoroughly experienced attendant.

My invention can be applied with particular advantage to oil engines operating with 35 solid fuel injection, as in this case under certain conditions, all valve gears can be dispensed with, the only means for controlling the engine consisting of a single controlling lever, serving to start, control 40 and stop the engine and, if necessary, to fill the fuel supply pipes.

In the drawings affixed to this specification and forming part thereof, two embodiments 45 of my invention are illustrated diagrammatically by way of example. In the drawings

Figs. 1 to 3 are sections of a fuel pump and starting device embodying my invention, the parts being shown in different positions,

Fig. 1 illustrating the normal working position, while

Fig. 2 shows the position of the parts during starting and

Fig. 3 the position when stopping or moving the pump by hand.

Fig. 4 is a section on line IV—IV in Fig. 1,

Fig. 5 is a similar view of a modification.

Referring now to Figs. 1 to 4, a cam 2 is fixed on a shaft 1, which may be the engine crank shaft, said crank through the medium of a lever 3, actuating the piston rod 4, the outer end of which forms the piston 5. Liquid fuel is supplied to the cylinder 11 of the pump through a passage 10. From the cylinder, the fuel flows through a pipe 12 to the injection nozzle of the working cylinder. In the casing 15 of the pump 11, the starting valve 17 is arranged in parallel to the pump, 16 being the seat and 18 the spindle of valve 17. Air under pressure is supplied to valve 17 at 13 and flows to the working cylinder through pipe 14.

In order to effect a connection between the starting valve spindle 18 and the drive of piston 5, so as to start the engine, a double-armed controlling lever 30 is arranged intermediate the spindles 18 and 4. Each arm of this lever embraces with its slotted ends 22 and 23 the pump spindle 4 and starting spindle 18, the end 22 extending intermediate projections 6 and 7 on spindle 4, end 23 intermediate a projection 19 at the lower end of the starting valve spindle 18 and a stationary projection 20. Double-armed lever 21 is pivoted to a rocking journal 25 of lever 30 which is linked to casing 15 by means of pivot 26. Journal 25 is arranged eccentrically to pivot 26 and by rocking lever 30 said journal can be carried into different positions.

The distance between the projections 6 and 7 on the piston rod 4 and 19 and 20 on the valve spindle 18 is so chosen, that in the middle position of journal 25 which corresponds to the position A of lever 30 (Fig. 1) the starting valve spindle 18 is not actuated, the end 23 of lever 21 moving freely between the stops 19 and 20. This is the position during normal running.

In order to start the engine, lever 30 is moved into the starting position B (Fig. 2), pin 25 and lever 21 being moved to the left, so that the end 22 of the lever engages the projection 6 on the piston rod 4. As the projection 6 is stationary when the engine is not running, it forms a rigid abutment for

the end 22 of lever 21 so that the lever will turn about it and the other end 23 will move the valve spindle 18 by the projection 19 to the left, so that the starting valve 17 is opened against the action of its spring 17^a and starting air is supplied to the engine.

After the engine is started, the starting valve 17 is opened and closed automatically by lever 21 being compelled to follow the movements of stop 6. When the engine is running normally, the lever 30 is returned to position A.

The controlling lever 30 and the double-armed lever 21 may also be used for stopping the engine by stopping the pump. To this end lever 30 is placed in the position C (Fig. 3), the journal 25 being thereby moved to the right and the end 23 of lever 21 engaging the fixed stop 20, whereupon the lever 21 will turn about this stop and engages projection 7 on the piston rod 4 of the pump. The spring 32 acting on the pump rod is thereby compressed and lever 3 is moved out of contact with cam 2, the pump 25 being brought to a standstill whereby the engine will be stopped also.

On lever 30 being returned to its initial position A, the spring 32 forces lever 3 back into contact with cam 2 whereby the pump 30 is again rendered operative. By repeatedly moving the lever 30 between positions A and C the pump piston can be made to reciprocate and the pump can be actuated by hand, in order to fill the fuel supply pipes 35 before starting the engine. Thus by actuating a single part, viz. lever 30, I am able to fill the fuel supply pipes before starting, to start the engine, to cause it to run normally after starting and to stop it.

40 In the embodiment of my invention illustrated in Fig. 5, the lever connecting the pump and the starting valve, is a single-armed lever 40.

The piston rod 4 here carries a roller 33 45 adapted to run in contact with cam 2. The starting valve 17 opens to the inside. The spindle 18 of the starting valve is connected with the piston rod 4 by the single-armed lever 40 pivoted to the piston rod 4 at 42. 50 The free end 41 of lever 40 is adapted to be displaced by means of a hand lever 30 and a rod 48. The lever 30 is fulcrumed at 49. To the starting valve spindle 18 there is secured a fork 44 provided with slots 45 55 engaged by a pin 43 on lever 40. The slots 45 are of such length that the pin 43 is free to move therein when the handle 30 is in the position A corresponding to normal running. In the position B, the lever 40 is 60 placed to the right so that pin 43 engages the right hand end of slots 45, thereby opening valve 17 and starting the engine. On lever 30 being shifted into position C, the spindle 18 of the starting valve 65 is released and the valve closed by its

spring, whereupon pin 43 engages the left hand end of the slots 45 so that lever 40 turns about pin 43 and carries the roller 33 of the piston rod 4 out of contact with cam 2 thus stopping the pump.

I claim:

1. Starting gear for internal combustion engines comprising a fuel pump, a starting air valve and manually adjustable means for operatively connecting said valve with said pump.

2. Starting gear for internal combustion engines comprising a fuel pump, means for transmitting power from said engine to said pump, a starting air valve and manually adjustable, means for operatively connecting said valve with said power transmitting means.

3. Starting gear for internal combustion engines comprising a fuel pump, a cam adapted to be actuated by said engine, a cam follower and a pull-back spring connected with said pump, a starting air valve and manually adjustable, means for operatively connecting said valve with said cam follower.

4. Starting gear for internal combustion engines comprising a fuel pump, means for transmitting power from said engine to said pump, a starting air valve, abutments forming part of said power transmitting means and of said valve, a coupling means mounted for rocking motion and for cooperation with said abutments and means for adjusting the pivotal point of said coupling means so that this latter can be shifted towards and away from said checks as required.

5. Starting gear for internal combustion engines comprising a fuel pump, means for transmitting power from said engine to said pump, a starting air valve, abutments forming part of said power transmitting means and of said valve, a coupling means mounted for rocking motion and for cooperation with said abutments, means for adjusting the pivotal point of said coupling means so that this latter can be shifted towards and away from said abutments as required, a casing forming part of said valve, and an abutment connected with said casing and adapted to form another pivot for said coupling means and to cooperate with said other abutment in severing the operative connection between said pump and said engine.

6. Starting gear for internal combustion engines comprising a fuel pump, means for transmitting power from said engine to said pump, a starting air valve, abutments forming part of said power transmitting means and of said valve, a coupling means mounted for rocking motion and for cooperation with said abutments, a fixed bearing, a pivot for said coupling means mounted for eccentric motion relative to said bearing and means for swinging said pivot around the axis of said bearing so that the coupling means can

be shifted towards and away from said abutments as required.

7. Starting gear for internal combustion engines comprising a fuel pump, means for transmitting power from said engine to said pump, a starting air valve, abutments forming part of said power transmitting means and of said valve, a coupling means mounted for rocking motion and for cooperation with said abutments, a fixed bearing, a pivot for said coupling means mounted for eccentric motion relative to said bearing and a hand lever for swinging said pivot around the axis of said bearing so that the coupling means can be shifted towards and away from said abutments as required.

8. Starting gear for internal combustion engines comprising a fuel pump, means for

transmitting power from said engine to said pump, a starting air valve, means for operating the pump piston, abutments forming part of said power transmitting means and of said valve, the abutment-forming part of said power transmitting means being formed on said piston operating means, a coupling means mounted for rocking motion and for cooperation with said abutments, a fixed bearing, a pivot for said coupling means mounted for eccentric motion relative to said bearing and means for swinging said pivot around the axis of said bearing so that the coupling means can be shifted towards and away from said abutments as required.

In testimony whereof I affix my signature.

HUGO JUNKERS.
